UNITED STATES PATENT OFFICE.

FRANTIŠEK JERMÁŘ, OF OPAVA, CZECHOSLOVAKIA.

SLUICE GATE.

Application filed March 26, 1925, Serial No. 18,532, and in Czechoslovakia May 8, 1924.

This invention relates to a hydrostatic device for regulating the flow of water over a weir, and consists in the provision of a water retaining flap which is hinged to the crest 5 of a rigid weir and supported by means of a strut on another flap which moves in a recess in the weir so as to form said recess into a closed conduit, the flaps being arranged so that both are horizontal and vertically in 10 alignment with each other in their lowest position and so that the supporting flap remains in all positions below the level of the crest of the weir.

The invention is illustrated in the accompanying drawing which represents a sectional view of the weir.

Mounted on the crest of a rigid weir 8 is a water retaining flap 1 which is hinged at 2 so that it can be adjusted in a vertical 20 plane for maintaining the water head in the upper pool 11 at different levels and regulating the flow of water over the weir. Another flap 4 is hinged to the weir 8 at 3, under the flap 1, and is connected to the latter 25 by means of a strut 6 which is hinged at 5 and 7 respectively to the two flaps. The flap 4 also moves in a vertical plane within a recess made for it in the weir 8, the recess being formed with a curved surface which is 30 concentric with the hinge 3 and which is swept by the flap so as to form a closed conduit which expands and contracts with the movements of the flap. When the flaps are 35 in a horizontal position, as shown by dotted lines, the conduit is reduced to a narrow channel 9 which can be set into communication, either with the upper pool 11 or with the lower pool 10. The flap 1 is supported 40 by means of the strut 6 on the flap 4 and changes its angular position together with the latter.

A channel 13 leading from the upper pool 11, communicates with the channel 9 and opens into the lower pool 10. Two sluice 45 valves 14 and 15 are arranged in the channel 13 at opposite sides of its communication with the channel 9, allowing the latter to be set into communication either with the upper or the lower pool.

When the conduit under the flap 4 is connected with the upper pool, the water pressure acts on the flap and raises the free ends of both flaps. A lip 12 on the weir 8 limits the upward movement. To increase the flow of water over the weir, the conduit is connected to the lower pool 10 until the desired angular position of the retaining flap is attained.

The flaps are arranged so as to be vertically in alignment with each other when in 60 their horizontal position. Thus the device has a contracted form and will occupy a very small space. The flap 4, moreover, remains below the level of the crest of the weir in all its positions, and it will therefore be acted 65 upon with sufficient water pressure for raising the flap 1 even from the lowermost position without auxiliary power sources. In a known arrangement wherein two flaps bear direct against each other, both are practically on a level with the water head in the lowest position and require auxiliary means for affecting the initial adjusting movement.

It should be noted that there is no sliding connection between the flaps and that the 75 supporting strut 6 is not subjected to any water pressure, so that very little friction occurs in the mechanism.

The strut 6 may either be composed of a continuous plate or a plurality of bars. 80

I claim:

A sluice gate for weirs comprising a water retaining flap hinged to the crest of the weir so as to move in a vertical plane, a controlling flap hinged to the weir in a similar manner below the retaining flap, the weir being recessed so as to form a closed conduit together with the controlling flap in all positions of the latter, and a strut pivoted to both flaps, the flaps being arranged so that 90 both are horizontal and vertically in alignment with each other in their lowermost positions and so that the controlling flap remains in all its positions below the level of the crest of the weir.

FRANTIŠEK JERMÁŘ.
